ALTERNATING-CURRENT-DISTRIBUTING SYSTEM.

1,035,394.

Specification of Letters Patent. Patented Aug. 13, 1912.

Application filed October 16, 1911. Serial No. 654,909.

To all whom it may concern:

Be it known that we, SEVERN D. SPRONG and WALTER E. MCCOY, citizens of the United States, residing at New York, in the county of New York and State of New York, have invented a certain new and useful Improvement in Alternating-Current-Distributing Systems, of which the following is a specification.

- 10 In alternating current distribution systems in order to obtain a better regulation at the customers' premises and to take advantage of the "diversity factor" in the various customers' demands, it has been found desirable to provide secondary mains supplied by comparatively few and large transformers. The aggregate transforming capacity is then less than in the case where each customer is supplied by a separate 20 transformer, because the maximum demand of all the customers supplied from the secondary main does not occur at the same instant. This secondary system is objectionable for the reason that in case a transformer 25 burns out or becomes short-circuited, there is a reverse flow of current from the secondary mains into the short-circuited transformer; the energy coming from the other transformers connected in multiple. The 30 proportion of the normal load borne by the transformer thus eliminated is thrown on the remaining transformers, and, in addition, as the transformer is short-circuited and becomes a heavy demand in itself, this 35 excess load is also thrown on the remaining transformers. There is, of course, a fuse between the secondary of the transformer and the secondary main of a capacity equal to the maximum output of the transformer. 40 Therefore it is seen that the current that can flow in the reverse direction from the secondary into the defective transformer must equal the rating of the fuse before the defective transformer will become isolated 45 by the blowing of its secondary fuse. It follows from this condition that the remaining transformers have not only to carry their normal load, but in addition their proportion of the normal load otherwise supplied by the defective transformer, and also 50 must supply enough energy to blow the fuse of the defective transformer so as to eliminate it from the secondary system. Where a large number of transformers is used, the

extra load thrown on each one would be 55 relatively small, but in practice the loss or drop in voltage in the secondary main is so considerable that the transformer nearest the one that is defective is called upon to carry much the larger proportion of the 60 load, which in turn causes it to blow out its fuse, thus shifting the heaviest portion of the load to the next nearest transformer with a similar result; so that in the end, all the transformers become disconnected in 65 turn, due to overload.

Our present invention overcomes this difficulty.

It is illustrated in the accompanying drawing, which is an electrical diagram, 70 showing two sets of apparatus, connected to primary and secondary mains, the said sets being alike, so that a description of one set will serve for both.

Similar numbers and letters of reference 75 indicate like parts.

It may be assumed that the potential on the primary mains 1, 2 is 2200 volts, which is stepped down by the transformers A, B to 110 volts on the secondary mains 3, 4, 80 to which secondary mains are connected the load circuits 5. On the step-down transformer A is a primary coil C, and secondary coil D.

Associated with each step-down transformer is a current transformer E, having three coils F, G, H. The terminals of coil F, which is of few turns and therefore of low voltage and high current capacity, are connected to the end terminals 6, 7 of a loop 90 fuse J. The terminals of coil G are connected respectively to secondary main 3, and to terminal 6 of fuse J. The terminals of coil H are connected respectively to primary main 2, and one terminal of primary coil 95 C on transformer A. The terminals of the secondary coil D on transformer A are connected to an intermediate terminal 8 on fuse J, and to secondary main 4. The coils G, H on transformer E have a ratio of ampere turns similar to that of coils D, C on transformer A, and are of opposite polarities, so that normally they neutralize one another, and induce no current on the third coil F.

100 The leads are as follows: from primary main 1, through primary coil C of step-down transformer A, to coil H of trans-

former E, to primary main 2, the usual fuses K being interposed; from secondary main 4, through fuse L, to secondary coil D of transformer A, to intermediate terminal 8 of fuse J, through one branch of the fuse J, to coil F and terminal 6, and through the other branch of the fuse directly to terminal 6, to coil G on transformer E, and secondary main 3.

10 In event of a transformer becoming short-circuited or burned out, the current coming on the secondary mains 3, 4, from the other transformers of the system, flows from said mains in the reverse direction to coil G. 15 This reverses the polarity of said coil, and puts it in series with coil H so far as the energizing effect of said coils on the core of transformer E is concerned. A high amperage current is then induced in coil F 20 which burns out fuse J, which is suitably proportioned for this result. This breaks the secondary circuit of transformer A, and so eliminates that transformer from the system. In other words, the third coil F 25 on transformer E is normally short-circuited by fuse J, which fuse is also over a portion of its length in the secondary circuit of the step-down transformer A. When transformer A is short-circuited within 30 itself, then the reverse current from the secondary main causes coils G, H, which hitherto neutralized one another's effect on coil F, to unite said effects, and induce in coil F a current strong enough to blow fuse 35 J, and so interrupt the secondary circuit of transformer A and so cut that transformer out of the system. Obviously, this can be accomplished only by the reversal of the current from the secondary mains. It is 40 to be noted that when the loop fuse J is blown, both branches of the fuse are interrupted, so that connection is broken from middle fuse terminal 8, through one branch, to secondary main 3, and through the other 45 branch, to coil F; also that in accomplish-

ing the present purpose, we eliminate all moving parts, such as switches, relays, etc.

It is preferable to place the branches of the fuse J sufficiently near together to cause rupture of one branch by the blowing of the 50 other, in case for any cause both branches shall not be blown simultaneously.

We claim:

1. An alternating current distributing system, comprising primary and secondary 55 mains, means for establishing a current on said secondary mains, two transformers interposed between said mains, one of said transformers having three coils, two of said coils being of opposite polarity and mutually neutralizing one another and respectively connected in series with the primary and secondary coils of the other transformer, and a fuse connected at one end to one of said last-named coils, at an intermediate point 60 to a secondary terminal of the other transformer, and at both ends to the terminals of said third coil.

2. An alternating current distributing system, comprising primary and secondary 70 mains, means for establishing a current on said secondary mains, a step-down transformer interposed between said primary and secondary mains, a current transformer having three coils, two of said coils being respectively interposed in the primary and secondary circuits of said step-down transformer and of opposite polarity mutually to neutralize one another, and a fuse short-circuiting the third coil and having a portion 75 of its length between said third coil terminals included in the secondary circuit of said step-down transformer.

In testimony whereof we have affixed our signatures in presence of two witnesses. 85
